UNITED STATES PATENT OFFICE.

JULIUS RITTER, JR., OF RACINE, WISCONSIN, ASSIGNOR TO HARTMANN TRUNK COMPANY, OF RACINE, WISCONSIN, A CORPORATION OF WISCONSIN.

SEPARABLE-SECTION TRUNK.

Application filed May 26, 1928. Serial No. 280,756.

This invention relates to improvements in separable section trunks.

Trunks, and particularly wardrobe trunks, are ordinarily formed with two hingedly connected sections which in use are vertically positioned and are adapted to be opened by being swung outwardly with respect to each other. In swinging the trunk sections to open position some space is required and 10 in cramped quarters, such as small ship cabins, state-rooms and the like, it is either inconvenient, due to the lack of space, to open the trunk, or the trunk in open position will occupy too much space.

15 It is, therefore, the primary object of the present invention to overcome the above objections by providing a trunk in which the two sections are separably hingedly connected together.

20 A further object of the invention is to provide a trunk of the class described in which the two sections are hingedly connected by a plurality of locking hinge members which may be released or disengaged 25 from one section, permitting the separation of the two sections for convenience in handling or storage.

A further object of the invention is to 30 provide in a two section trunk, a plurality of locking hinge members connecting said sections and all operable simultaneously by a common means to release one section to permit its disengagement from the other section.

35 A further object of the invention is to provide releasable trunk section hinging locks which may be released or unlocked when the sections are only slightly opened with respect to each other.

40 A further object of the invention is to provide a trunk wherein the two sections are disconnectibly joined by lock hinges, which latter are arranged for easy connection between the hasps and the escutcheons and 45 latches when the trunk sections are to be joined.

A further object of the invention is to 50 provide a separable section trunk which is of very simple construction, is easily manipulated, is strong and durable, and is well adapted for the purposes described.

With the above and other objects in view, the invention consists of the improved separable section trunk, and its parts and com-

bination as set forth in the claims, and all 55 equivalents thereof.

In the accompanying drawings in which the same reference characters indicate the same parts in all of the views:

Fig. 1 is a vertical sectional view of the 60 separable section trunk with the two sections connected and closed with respect to each other;

Fig. 2 is a cross-sectional view indicated on line 2—2 of Fig. 1 only showing the sections swung open with respect to each other;

Fig. 3 is an enlarged fragmentary detail sectional view showing the trunk sections closed and one locking hinge in engaging position, it being shown in disengaged position in dotted lines; and

Fig. 4 is a detail sectional view taken on line 4—4 of Fig. 3.

Referring now more particularly to the drawings, it will appear that the numeral 75 8 indicates a wardrobe trunk having a wardrobe section 9 and a drawer section 10. Each of said sections has an open side and said open sides are brought together with the adjacent wall portions of the sections 80 in overlapping engagement when the sections are closed.

The invention resides particularly in the means employed for hingedly and disconnectibly joining the sections 8 and 9. For 85 that purpose a plurality of spaced hinging lock members 11 is provided. Each lock comprises a fixed plate portion 12 which is secured to the side wall of one of the trunk sections 10, and having a pair of curved lug 90 portions 13 between which the curved tongue portion 14 of a hasp member 15 extends, a pivot rod 16 being extended through the lug portions 13 and the tongue portion 15 to pivotally joint the hasp member to the plate 95 portion. Each pivot rod 16 has wound thereabout the intermediate portion of a confined spring 17 arranged so that its end portions bear against the plate portion and hasp 100 respectively, so that when the hasp is released, its spring will urge it to the dotted line position shown in Fig. 3. Each hasp has an inwardly projecting lug portion 18 formed with a squared opening 19.

The wardrobe section 9 has mounted on its 105 side wall in juxtaposition to the hasp members 15, a plurality of escutcheons 20 adapted to receive adjacent hasp members when

the same are in locked position. The hasp members are adapted to be releasably held in locked position within their escutcheons by a plurality of spring urged latches 21. 5 Each escutcheon is formed with an inwardly projecting casing portion 20' and a latch is vertically movably mounted within each casing portion. Said latches are formed with depending shank portions 22 extending 10 through the lower end portions of the casings and also with laterally projecting headed guide pins 23 projecting through vertical slots 24 in the side walls of the casing. Coiled springs 25 surround the shank 15 portions 22 within the casings and urge the latches into operative positions. Each latch is formed with an angularly shaped engaging head portion 21' having an inclined inner edge adapted to ride into the opening 20 19 of its hasp lug 18 for locking purposes, as in Fig. 4.

All of the latches 21 are adapted to be operated simultaneously and for that purpose an elongated vertically movable rod 26, 25 formed with a handle 27 at its upper end portion, is slidably mounted in a bracket 28 on an inner wall of the trunk section 9. Levers 29 are pivotally mounted below each latch and the inner end portion of each lever 30 is pivotally connected to the rod 26. The outer end portion of each lever is connected to the lower end portion of the adjacent latch shank 22 by means of several links 30.

By this arrangement, when the rod 26 is 35 moved vertically upwardly, the levers 29 will be caused to pivot in a clockwise direction in Fig. 1, drawing downwardly on the latch shanks 22 to release the latches from the hasps. When the rod 26 is released the 40 springs 25 surrounding the latch shanks will return said latches to normal position.

Normally, all of the hasps are latched, thereby connecting the adjacent edge portions of the rear walls of the trunk sections 45 and permitting one section to be hingedly moved with respect to the other section, this being allowed by the pivot rods 16 which connect each hasp member with its plate portion. When the trunk sections are closed 50 as for transportation, the front portions of said sections are held together by ordinary locking means, indicated at 31 and 32 in Fig. 2. If it is desired to separate the trunk sections for convenience in use in close quarters, 55 or for handling or storage, the front portions of the sections are opened slightly and then by means of the common mechanism previously described, all of the latches are released from their respective hasps, and the 60 hasps, due to their springs 17, will open, as shown in dotted lines in Figs. 2 and 3, and separate the sections. In closing the hasps, to join the sections, the hasps are pushed into their escutcheons and the inclined portions 65 of the latch heads will cause the same to ride

into their respective hasp openings 19, thereby locking the hasps and again hingedly joining the trunk sections.

From the foregoing description it will be seen that the improved separable section 70 trunk is of simple and novel construction, and is well adapted for the purposes described.

What I claim as my invention is:

1. A trunk, comprising a pair of sections, 75 hinge members secured fast to one of the sections and releasably engageable with the other section, and latch members releasably engageable with releasable portions of said hinge members. 80

2. A trunk, comprising a pair of sections, a plurality of hinge members secured fast to one of the sections and releasably engageable with the other section, a plurality of latch members mounted within said other 85 section for releasable engagement with said hinge member, and means for jointly operating said latch members.

3. The combination with a trunk having a pair of complementary sections, of a plate 90 member secured to a wall of one of said sections, a hasp pivotally secured to said plate member, and a latch member carried by the other trunk section and releasably engageable with said hasp, the latch member when 95 engaged with the hasp permitting hinging movements of one trunk section with respect to the other.

4. The combination with a trunk having 100 a pair of complementary sections, of a plurality of spaced plate members secured to a wall of one of said sections, a hasp member pivotally connected to each plate member, a plurality of latch members operably secured to the other trunk section, each 105 latch being releasably engageable with a hasp member, and means for jointly moving said latches to hasp releasing position.

5. The combination with a trunk having 110 a pair of complementary sections, of a plurality of spaced hasps pivotally secured to a wall of one of said trunk sections, each hasp being provided with a spring exerting an expansive opening force thereagainst, a plurality of latch members operably secured to the other trunk section, and each releasably engaging a hasp member, each latch being provided with a spring to releasably hold it in latching position, an operating member mounted within said last-mentioned 115 trunk section, and connections between said operating member and each latch whereby a movement of the operating member will be transmitted to said latches to jointly move all of the same to releasing positions. 120

6. The combination with a trunk having a pair of complementary sections, of a plurality of spaced plate members secured to a wall of one of said sections, a hasp member pivotally connected to each plate member 130

and having its outer end portion formed with an inwardly projecting apertured lug portion, each hasp member being provided with a spring exerting an expansive force 5 against its inner surface, a plurality of spaced escutcheons mounted in a wall of the other trunk section and adapted to receive the apertured lug portions of their adjacent hasp members, a plurality of latch members 10 operably secured to the other trunk section adjacent the escutcheons and each releasably engaging a hasp member, each latch

being provided with a spring to releasably hold it in latching position, an operating member mounted within said last-mentioned 15 trunk section, and connections between said operating member and each latch whereby a movement of the operating member will be transmitted to said latches to jointly move all of the same to releasing positions. 20

In testimony whereof, I affix my signature.

JULIUS RITTER, JR.
